UNITED STATES PATENT OFFICE.

STANLEY A. COHEN, OF NEW YORK, N. Y.

DESIGN FOR THE BACKS OF PLAYING-CARDS.

SPECIFICATION forming part of Design No. 19,173, dated June 25, 1889.

Application filed April 8, 1889. Serial No. 300,445. Term of patent 14 years.

To all whom it may concern:

Be it known that I, STANLEY A. COHEN, of the city of New York, in the county and State of New York, have invented and produced a new and original Design for the Backs of Playing-Cards, of which the following is a specification, reference being had to the accompanying drawing, forming part thereof.

My design consists of a surface ornamentation of lace work on the back of a playing-card. This lace-work is shown by the letters *a a, &c.*, such being the border, and *b* the lace-work within the border, with a center of

lace-work *c*, upon which are lace flowers *d d* and circular ornaments *e e*. The essential feature of my design, however, consists in the lace-work border and the central rectangular ornamental panel.

I claim:

The design of back for playing-cards, substantially as shown and described.

STANLEY A. COHEN
